US0D1026494S

(12) **United States Design Patent** (10) **Patent No.:** **US D1,026,494 S**
(45) **Date of Patent:** **** May 14, 2024**

(54) **STORAGE BOX**

(71) Applicant: **NINGBO BOTONG PLASTIC CO., LTD**, Ningbo (CN)

(72) Inventor: **Junhao Tong**, Ningbo (CN)

(73) Assignee: **NINGBO BOTONG PLASTIC CO., LTD**, Ningbo (CN)

(**) Term: **15 Years**

(21) Appl. No.: **29/854,902**

(22) Filed: **Sep. 29, 2022**

(30) **Foreign Application Priority Data**

Jun. 20, 2022 (CN) 202230379276.0

(51) **LOC (14) Cl.** **06-06**

(52) **U.S. Cl.**

USPC **D6/515**; D3/304

(58) **Field of Classification Search**

USPC D3/295, 304, 311, 310; D6/515, 675, D6/675.1, 705; D19/75, 86, 92; D9/733
